NECKLACE OR SIMILAR ARTICLE

Jacques Fath, Paris, France, assignor to Weinreich Brothers Company, New York, N. Y.

Application August 31, 1949, Serial No. 4,789

Term of patent 3½ years

(Cl. D45—16)

To all whom it may concern:

Be it known that I, Jacques Fath, a citizen of the Republic of France, residing in Paris, France, have invented a new, original, and ornamental Design for a Necklace or Similar Article, of which the following is a specification, reference being had to the accompanying drawing, forming part thereof.

Fig. 1 is a front elevational view of a necklace or similar article showing my new design,

Fig. 2 is an edge view thereof.

Portions of the necklace are shown in broken lines for convenience of illustration only.

I claim:

The ornamental design for a necklace or similar article, substantially as shown and described.

JACQUES FATH.
